UNITED STATES PATENT OFFICE.

ERNEST WYMAN SAVORY, OF CLIFTON, BRISTOL, AND ALFRED FRANCIS BATTEY, OF LONDON, ENGLAND.

WIPING DEVICE FOR DIE-STAMPING MACHINES.

1,100,153.

Specification of Letters Patent. Patented June 16, 1914.

Application filed June 11, 1913. Serial No. 772,940.

To all whom it may concern:

Be it known that we, ERNEST WYMAN SAVORY, of Park Row Studios, Clifton, Bristol, Gloucester, England, fine-art publisher, and ALFRED FRANCIS BATTEY, of 11 Carthusian street, London, England, engineer, have invented certain new and useful Improvements in and Relating to Wiping Devices for Die-Stamping Machines, of which the following is a specification.

10 This invention relates to wiping devices for die stamping machines of the type in which the die is moved from the die press to an inking device and back again.

15 The object of this invention is to provide an improved device for wiping the die after it has been inked.

20 A device made in accordance with this invention comprises a web of paper adapted to be wound from one spool onto another and to pass over the surface of a wiper, means for intermittently raising and lowering the wiper so that the paper intermittently comes in contact with the die, means for imparting oscillating rotary movement 25 to the wiper, and means for traveling the paper with the surface of the wiper as the wiper rotates in one direction, during the period that the die is passing under and in 30 contact with the paper, the motion of the die being in the opposite direction to the travel of the paper.

35 Figure 1 is a front elevation of a part of a die stamping press showing a wiping device made in accordance with this invention. Fig. 2 is a back elevation of the same. Fig. 3 is a plan showing the spools. Fig. 4 is a plan of the wiper. Fig. 5 is an end view of Fig. 4.

40 *a* is the frame of the machine, *b* and *c* are spools mounted on the frame, *d* is a web of paper adapted to be wound from the spool *b* to the spool *c*.

45 *e* is a wiping drum mounted on a spindle *f* in bearings *g*. The bearings are mounted in a guide *h* and supported by a spring *i*. The paper passes under the wiping drum *e*. The spool *c* is mounted in a shaft *j* which carries a friction disk *k*.

50 *m* is a pulley loose on the shaft *j* and adapted to make friction contact with the disk *k*.

55 *n* is a nut and *o* a spring for adjusting the friction, the pulley *m* is driven continuously by a pulley not shown.

The wiping drum *e* is adapted to be lowered by means of a cam *p* on the shaft *q* which presses on the bearing block *g* against the spring *i*. Oscillating rotary movement is given to the shaft *q* by means of crank *r* 60 connecting rod *s* crank *t* shaft *v* crank *w*, and connecting rod *x*.

y is a bowl on the rod *x* which is kept against the face of the cam *z* by the spring not shown. The cam *z* is on the main shaft 65 of the die press. The wiping drum *e* is adapted to be oscillated on its axis by the crank *3* and connecting rod *4* which receives reciprocating movement from the lever *5*. The lever *5* is pivoted at *6* and carries a bowl 70 *7* actuated by a cam *8* suitably driven. The rod *4* is held in contact with the crank *3* by spring *9*. The position of the end of the rod *4* on the crank *3* and the consequent amount of oscillating movement of the 75 drum *e* is adjusted by connecting rod *10*, crank *11* shaft *12* and handle *13*. The handle *13* is adapted to be held in any position on the quadrant *14* by spring bolt in the handle. 80

In operation the die is adapted to be traveled from the inking device to the press. When the die is being inked the wiping drum is in its raised position, after the die has been inked and as it approaches the 85 wiping device, the wiping drum descends and just as the die comes under the wiping drum the drum is caused to rotate in a direction contrary to the travel of the die. The paper being traveled over the face of 90 the die, effectually wipes the surface of the die, the die travels on the press and receives a blow, the wiper then ascends and is rotated in the reverse direction at the same time the slack of the paper is wound up on 95 the spool *c* and the die returns to the inker. The spool *b* is held against free rotation by a spring pressed disk *16*, the pressure being adjusted in relation to the pressure of the spring *o* on the friction disk *k*, so that 100 the drive of the pulley *m* on the disk *k* is not sufficient to rotate the spool *c* to draw the web of paper off the roll *b* until assisted by the pull of the wiper when pressing the paper on to the die. The wiping drum is or 105 may be covered with a pad or fabric which can be tightened in any well known manner, such as shown in Figs. 4 and 5 in which the drum *e* is provided with a recess *15* in the periphery of the drum. The side plates 110

16 of the drum form walls at the sides of the recess 15, which walls form bearings for a shaft 17 which passes through the recess and which is provided at one end with a 5 ratchet wheel 18 and at the other with a collar 19, the collar and ratchet preventing longitudinal movement of the shaft. A pawl 20 is pressed normally into engagement with the ratchet 18 by a spring 21. A 10 squared end 22 is provided on the shaft 17 for turning the same when it is desired to tighten the fabric, the other end of the fabric being secured to pegs 23 disposed in the recess.

15 What we claim and desire to secure by Letters Patent is:—

1. A wiping device for use in die stamping machines comprising a frame, a guide and two spools mounted on the frame, a wiping-drum mounted in the guide, said wiping-drum being provided with a pad and means for tightening the pad, a web of paper adapted to be wound from one spool to another and to pass over the surface of the wiping pad, means for intermittently raising and lowering the wiping drum from and to pressing-contact with a die as the die passes beneath the same, means for imparting oscillatory movement to the wiping 25 drum, said wiping drum as it rotates in one direction traveling the paper therewith, and means for winding up the paper traveled by said wiping-drum.

2. A wiping device for use in die stamping machines comprising a frame, a guide and two spools mounted on the frame, a wiping-drum mounted in the guide, said wiping drum being provided with a pad and means for tightening the pad, a web of paper 30 adapted to be wound from one spool to another and to pass over the surface of the wiping pad, means for intermittently raising and lowering the wiping drum from and to pressing-contact with a die as the die passes beneath the same, means for imparting oscillatory movement to the wiping drum, said wiping drum as it rotates in one direction traveling the paper therewith, and means for winding up the paper traveled by said wiping-drum.

35

40

45

ing oscillatory rotary movement to the wiping-drum, said wiping-drum as it rotates in one direction traveling the paper therewith, means for winding up the paper traveled by said wiping drum, said traveling of the 50 paper taking place during the period the die is passing under the paper and in contact with the paper, the travel of the paper being in the opposite direction to the motion of the die.

55

3. A wiping device for use in die stamping machines comprising a frame, a guide and two spools mounted in the frame, a wiping drum mounted on bearings in the guide, said wiping drum being provided with a 60 pad, means for tightening the pad, a spring adapted to press the wiping-drum in one direction in the guide, a web of paper adapted to be wound from one spool to another and to pass over the surface of the wiping 65 pad, means for driving the spool in which the paper is wound comprising a pulley driven continuously and a friction clutch between the driving pulley and winding-spool, means for holding the spool from 70 which the paper is wound against free rotation, means for intermittently pressing the wiping drum and the paper wound therearound into contact with the die against the action of the spring, means for imparting 75 oscillating rotary movement to the wiping-drum and traveling the paper therearound, said traveling unwinding the paper from one roll and the friction clutch acting to turn the other roll to wind the slackened 80 paper thereon.
